UNITED STATES PATENT OFFICE.

ERNEST ROSS, OF EAST ORANGE, NEW JERSEY, ASSIGNOR, BY MESNE ASSIGNMENTS, TO RADIO CONDENSER COMPANY, OF CAMDEN, NEW JERSEY, A CORPORATION OF NEW JERSEY.

STATOR-PLATE ADJUSTMENT FOR VARIABLE CONDENSERS.

Application filed February 23, 1926, Serial No. 89,845. Renewed November 23, 1927.

- This invention relates to variable condensers as used in connection with radio apparatus receiving sets and more specifically to the stator plates used therein.
- 5 Variable condensers of this type ordinarily consist of a rigid frame firmly held within a cabinet and in which is fixed a plurality of stator plates arranged in uniformly spaced relation.
- 10 Interposed between each pair of stator plates is a rotor plate, all of the rotor plates being fixed on a shaft or mandrel controlled and actuated by a manually operable knob to move the rotor plates radially relative to the stator plates, and means are sometimes provided to shift the shaft, or the rotor plates thereon, laterally with reference to the stator plates to cause centralization therebetween.
- 15 Such shifting devices are necessarily quite complicated, inconvenient to adjust, due to their practical inaccessibility, and are therefore neglected notwithstanding the necessity of a uniform air gap between the several plates in order to obtain the best results.
- 20 It is an object of the present invention to eliminate the necessity of laterally adjusting the rotor plates, permitting them to be fixedly secured in proper spaced relation on their spindle, and also obviating any requirement for longitudinal adjustment of the spindle to accomplish the same purpose.
- 25 It is a further feature to permit the permanent, fixed installation of a stator plate frame within a cabinet, means being provided in the frame for shifting the group of previously assembled stator plates, as a unit, laterally in either direction conformably with respect to the rotor plates.
- 30 Another aim is to provide a simple, effective and easily operated device for adjusting the stator plates without affecting their support frame in any respect.
- 35 These and lesser important objects are accomplished by the novel and practical construction, arrangement and combination of few and simple parts hereinafter described and delineated in the associated drawing, constituting a material part of this disclosure, and in which:—
- 40 Figure 1 is a top plan view of a variable condenser made in accordance with the invention, the rotor elements being omitted.
- 45 Figure 2 is a longitudinal sectional view taken on line 2—2 of Figure 1.
- 50 Figure 3 is a transverse sectional view taken on line 3—3 of Figure 1.
- 55 Figure 4 is a perspective view of a group of parts used in the structure, shown in detail.
- 60 In common with other variable condensers the support frame consists of upright plates 10 and 11, having ordinary means, not shown, for attachment to the wall of a cabinet.
- 65 These frame plates are maintained in fixed spaced relation by a series of metal tubes 12 uniform in length and having their ends squarely cut to contact with the inner faces of the plates.
- 70 The stator plates 13 consist of a single continuous strip of metal stamped to produce a plurality of identical profiles bent at their connected ends to produce a series of integrally united plates.
- 75 The profiles of these several plates 13 include recesses 14 near one end in their upper edges in which the rotor plate carrying spindle may enter, the rotor plates being shown in broken lines and designated by the numeral 15.
- 80 Extending from the opposite convex edges of the stator plates are lugs 16 having registering openings through which pass rods 17 provided with screw threads at each end.
- 85 A series of spacers 18 are arranged intermediate the plates on the rods 17, these spacers being uniform in thickness and make intimate contact with the lug surfaces, the plates and spacers being clamped between nuts 19 adjustable on the ends of the rods 17.
- 90 The tubes 12 are cut away on one side intermediate their ends, as at 20, and are of such internal diameter as to receive the lugs 16, spacers 18 and nuts 19 through the recess 20, the nuts 19, preferably hexagonal on their exteriors, extending past the cut-out recess into the ends of the tubes, as best seen in Figure 3, but do not reach to the plates 10 and 11, spaces 21 intervening.
- 95 The tubes 12 are held in position between the support plates 10 and 11 by screws 22 passing through openings in the plates and engaging the outer ends of the nuts 19, the engaged heads of the screws impinging

2
against the outer surfaces of the support plates.

It will be understood from the foregoing that the stator plates 13, spacers 18 and rods 17 may be assembled and held by the nuts 19 within the tubes 12, and that these elements are entered as a unit between the plates 10 and 11 to receive the screws 22, their heads clamping the structure firmly together.

If it be desired to adjust the stator plates 13 relative to the rotor plates 15, to equalize the air space between them, it may be easily accomplished by slackening the clamp screws on the side it is desired to move from, as for instance, the support plate 10, and tighten the screws 22 at the other side 11, drawing the unit in the direction of the arrow shown in full lines in Figure 3, the several parts moving freely within the tubes 12 which remain stationary.

Obviously a resultant movement in the opposite direction, indicated by the arrow shown in broken lines, may be obtained by proper manipulation of the combined clamping and adjusting screws 22.

It is to be noted that the means for adjustment is not limited to stator plates of integral construction, but is widely and generally applicable to any of the usual types of condenser construction.

Thus a positive adjustment of the stator plates is readily obtained within such limits as is desirable and the same is accomplished in an easy manner, while the rotor plates are maintained in the integrity of their original assembly.

Although I have described my improvements with considerable detail and with respect to certain detail forms of my invention, I do not desire to be limited to such details since many changes and modifications may well be made without departing from the spirit and scope of my invention in its broadest aspect.

Having thus described my invention, what I claim as new and desire to secure by Letters Patent, is:—

1. A variable condenser including a plurality of rods, a plurality of stator plates 50 assembled as a unit on said rods, tubes in which said rods are slidably enveloped, said tubes having recesses to receive said rods, rigid supports between which the unit is mounted, and means to shift the unit laterally between the supports lengthwise within the tubes.

2. A variable condenser including a plurality of stator plates, rods on which said plates are mounted, said rods being threaded at their ends, spacers on said rods intermediate said plates, elongated nuts on said rods for clamping the plates and spacers, spaced supports for said plates, and screws 60 passing through said supports to engage said nuts for adjusting said rods lengthwise 65 therebetween whereby shifting of said plates is accomplished.

3. A variable condenser including a plurality of stator plates, rods on which said plates are mounted, spacers on said rods intermediate said plates, nuts for clamping the plates and spacers on said rods, tubes 70 partially enveloping said rods, rigid supports held in spaced relation by said tubes, 75 and screws passing through said supports to engage said means whereby said plates may be shifted laterally.

4. In a variable condenser having rotor and stator plates, said stator plates having perforate projections, rods passing through said projections, spacers on said rods between adjacent plates, clamp nuts on said rods binding the plates and spacers into a unit, said nuts extending beyond the rods, 80 tubes having recesses to receive said rods, spacers and plate projections, supports spaced by said tubes, and screws passing through said supports to engage in the extending ends of said nuts, whereby the plate 85 units may be moved laterally with reference to said rotor plates.

This specification signed this 8th day of February, 1926.

ERNEST ROSS.
